UNITED STATES PATENT OFFICE.

SIDNEY C. CLARK, OF PORT CLINTON, OHIO, ASSIGNOR TO AMERICAN GYPSUM COMPANY, OF PORT CLINTON, OHIO, A CORPORATION OF OHIO.

PLASTER BOARD.

Application filed January 6, 1922. Serial No. 527,324.

This invention relates to improvements in plaster board and more particularly to an improved method of constructing plaster board so as to provide a more durable and stronger product, these qualities not being confined to its characteristics as a wall constructing material but also its ability to resist breakage and damage in the handling incident to its manufacture and transportation prior to its ultimate application upon a wall structure.

The novel features of the invention pertain more especially to the manner in which the edges are treated in order to secure the advantages of uniform and smooth finish, and marginal strength and resistance against damage in handling. The treatment of the edges, ordinarily referred to as sealing or binding, involves a process of manufacture whereby the margins of the covering sheets of fibrous material are folded over the edges of the body of plaster in a novel manner calculated to produce advantages not found in plaster board manufactured by processes now in use.

The construction of the plaster board or method of binding the edges thereof is hereinafter described in detail, and illustrated in the accompanying drawings, in which

Fig. 1 is a perspective view of a piece of plaster board, showing the manner in which the edges are treated.

Fig. 2 is a view in cross section of the board taken on line 2—2 of Fig. 1.

Plaster board, as commercially known, is a material used extensively in the construction of the walls of buildings and as ordinarily manufactured, consists of a layer of plaster superimposed between sheets of heavy paper or other fibrous material, the latter providing the qualities of durability and toughness that is completely lacking in the plaster, thereby enabling the product to be marketed in the form of sheets, ready to be nailed or otherwise applied to the wall structure.

As hereinbefore suggested, a sheet of plaster board comprises a body 1 of plaster of the desired thickness, a bottom covering sheet 2 of tough paper or other fibrous material, and a similar top covering sheet 3. As will hereinafter appear, the treatment of both the bottom and top covering sheets is identical, therefore, it is to be understood

that the distinction is one of convenience only in describing the product, as illustrated.

The covering sheets 2 and 3 are somewhat wider than the body 1, being provided with marginal strips 4—4, which extend beyond the edges of said body and constitute the parts utilized in the formation of the edges of the finished product. These marginal portions 4—4, although integral with the covering sheets, are preferably to be considered separate therefrom for the purpose of a clearer understanding of the structure, and for the same reason, each of the marginal portions 4—4 will be considered as consisting of two parts, presently to be indicated.

Considering one of the edges, and with particular regard to the process by which the edge is formed, the marginal portions 4—4 being folded inwardly and toward each other at right angles to their respective sheets 2 and 3, against the exposed edge surface of said body along fold lines 5—5, for a distance substantially equal to one-third the thickness of the body 1, forming what may be termed end strips 6—6. At the extremity of the end strips the remaining portions or flaps 7—7 are folded again at right angles to the end strips along fold lines 8—8, and extend edgewise into the body, parallel with each other and to the main sections of the covering sheets. In other words, each marginal flap 4 is folded twice at right angles, once against the edge, and again at right angles to the edge so that the marginal flap 7 is embedded in the body 1. The length of the marginal flaps or embedded edges 7—7 of the covering sheets may be varied, although preferably extending inwardly from the edge of the board a distance sufficient to provide marginal areas of ample width through which the nails may be driven in applying the board to a wall.

In practice, the plaster in plastic state is applied to the bottom sheet, the upper sheet applied, and the margins folded in substantially final form prior to the passage between rolls, whereby the plastic material is spread evenly and to a uniform thickness throughout the width of the board, filling the spaces between the flaps 7—7 and the outer sections of the sheets, as well as the space between the flaps themselves in the form of a comparatively thin layer 9, extending outwardly

2
to and flush with the edge surface of the board and the edge strips 6-6 of the covering sheets. The exposed edges of the layer 9 are finished in order to provide a smooth 5 edge surface throughout. As a preferred construction, the flaps 7-7 are spaced from the outer surface coverings, a distance substantially equal to one-third the thickness of the body, thus the thickness of the layer 10 9-9 of the body would be substantially equal to one-third of its total thickness. However, these proportions may be varied to some extent, as for instance, the flaps 7-7 15 may be brought more nearly together and a very thin layer of plaster separating them, indeed the actual contact of the flaps, and the absence of an intermediate layer of plaster would be a satisfactory construction.

It is to be observed that in constructing 20 plaster board in this manner the top and bottom sheets are independently treated in forming the sealed edges, that is to say, no overlapping or joining of the sheets is resorted to in the sealing operation, each sheet, 25 on the other hand, being anchored or embedded independently of the other in the body with no edges exposed or joints appearing on the surface of the board. It follows, therefore, that both sides of the board are 30 identical in every respect, and smoothly finished throughout.

The improved structure has special advantages pertaining to the quality of the product as a building material. In the first 35 place, the embedded margins of the sheets not only form a permanent connection between the parts, but spaced as they are

throughout the thickness of the body, and extending along the edges thereof, provide layers of reinforcement not only acting to 40 provide a firmer edge, as a protection against injury in handling, but as a means for insuring a more permanent and tenacious adherence of the board to the wall structure inasmuch as the margins thereof consist of four 45 layers of thicknesses of the covering paper through which the nails or other fastening means may be driven. The interspersing of the plaster with paper manifestly increases the resistance of the board to the formation 50 of cracks in the body, resulting from the driving of the nails through the margins, or from accidental hammer blows.

Although I have described and illustrated a preferred construction for plaster board, 55 it is manifest that the structural details may be variously modified without departing from the spirit of the invention, and therefore, I do not wish to be limited except insofar as the invention is specifically set forth 60 in the appended claim.

I claim as my invention:

A plaster board comprising a plaster body having covering sheets adhering to the opposite faces thereof, and folded over the 65 junctions of the side edges and faces thereof, and folded again into and embedded in the plaster body in spaced relation so as to expose a portion thereof along the side edges of said plaster board. 70

In witness whereof, I hereunto subscribe my name this 30th day of December, A. D., 1921.

SIDNEY C. CLARK.
